UNITED STATES PATENT OFFICE.

HEINRICH DREWELL, OF CHARLOTTENBURG, GERMANY.

PERFORATING-MACHINE.

1,190,736.

Specification of Letters Patent. Patented July 11, 1916.

Application filed September 17, 1913. Serial No. 790,218.

To all whom it may concern:

Be it known that I, HEINRICH DREWELL, a subject of the German Emperor, residing at Charlottenburg, Germany, have invented 5 new and useful Improvements in Perforating-Machines, of which the following is a specification.

My invention relates to devices for driving the bands in register-band perforating-10 machines which are employed in setting type, telegraphing, and so on. Such bands are inserted into the machine in the form of large stock rolls. The very rapid intermittent feed of the band occasioned by the mode 15 of operation of the machine causes difficulties, however, because the inertia of the roll impairs the uniformity of the steps in which the band is fed. In order to obviate this defect devices have heretofore been pro-20 posed in which the band is unwound from the stock roll by means of a special driving device which is actuated by means of a readily engaged clutch or by means of electric contact devices.

25 A primary object of my invention is to provide an improved device for unwinding the band from the stock roll which is simpler than devices heretofore employed. To this end, I provide an auxiliary driving de-30 vice which requires no special clutch in order to be set working. On the contrary, owing to the continuously running friction rollers which I employ, the operation of my auxiliary driving device is regulated di-35 rectly by the tension of the band, the em- ployment of additional intermediate mem- bers being dispensed with.

One embodiment of my invention is represented by way of example in the accom-40 panying drawing, wherein one preferred form of apparatus according to my invention is represented in elevation.

Referring to the drawing, the perforated band is inserted into the machine in the 45 form of a large stock roll 1 on a pin 2 in such manner that the roll can readily rotate about the pin. The band 3 is led from the roll 1 over a friction roller 4, then over a second friction roller 5, and then through a 50 system of transverse ribs 6 and 7 into the gap between the matrix 8 and the punches 9. The band then goes through a step-by-step feeding device consisting of two rubber-covered feed rollers 10 and 11, the for- 55 mer being carried by an axle 12 which is fed

one tooth by means of a ratchet-wheel 13 driven by the main shaft 14 at each revolution of the latter. This ratchet-wheel is fed by a pawl 15 which is pressed by a spring 16 into the tooth of the wheel 13 60 and is connected with a strap 17 which surrounds an eccentric 18. The purpose of the friction rollers 4 and 5 is to facilitate the unwinding of the band 3 from the roll 1 and to prevent unequal steps being produced owing to the heavy mass of the roll when the band is fed step by step. To this end, the two friction rollers 4 and 5 are constantly driven. The roller 5 is mounted directly on the lengthened axle 20 of the motor 21. In proximity to this roller 5 on the same axle is mounted a gear wheel 22 which meshes with a gear wheel 23 rigidly connected with the roller 4.

As long as the motor 21 runs and the ma-75 chine is working the rollers 4 and 5 rotate. They drive the band so far that it lies loosely on the roller 4 and hangs below the roller 5. As soon as the band is subjected to tension owing to its being fed step by 80 step by means of the feed rollers 10 and 11, and the band bears firmly against the rollers 4 and 5, in consequence of its friction with these rollers the band is powerfully fed forward and unwound from the roll 1. 85 The rollers 4, 5, 10 and 11 are preferably covered with india-rubber or with a similar mass which produces sufficient friction with the band. The roller 11 is pressed by springs of suitable strength against the 90 roller 10 in order to insure that the band is certainly drawn forward. Instead of the two friction rollers 4 and 5 I may employ only one. I may however employ three or more constantly rotating friction rollers 95 when the band 3 will move in still more uniform steps. Nevertheless, in general, two friction rollers 4 and 5 are sufficient.

I claim:

1. In means for making perforated bands 100 for operating automatic type-setting or line-casting machines, the combination, with a step-by-step feeding device for feeding band from a stock roll step by step, of a plurality of continuously driven friction rollers 105 lapped by the band, the action of which friction rollers depends upon the tension of the band caused by the step-by-step feeding device.

2. In means for making perforated bands 110

for the automatic operation of type-setting or line-casting machines, the combination of intermittently driven feed rollers, an escapement device, an eccentric operating said escapement device and driving said feed rollers, a member carrying a stock roll of band, the band passing between said feed rollers and lapping said friction rollers and being adapted to be transferred by said fric-

tion rollers when put under tension by said 10 feed rollers.

In testimony whereof I have signed my name to this specification in the presence of two subscribing witnesses.

HEINRICH DREWELL.
